UNITED STATES PATENT OFFICE.

LEWIS O. McELHANEY, OF GLASFORD, ILLINOIS.

PICK.

1,388,872.

Specification of Letters Patent. Patented Aug. 30, 1921.

Application filed June 4, 1920. Serial No. 386,594.

To all whom it may concern:

Be it known that I, LEWIS O. McELHANEY, a citizen of the United States, residing at Glasford, in the county of Peoria and State 5 of Illinois, have invented certain new and useful Improvements in Picks; and I do hereby declare that the following is a full, clear, and exact description of the invention, which will enable others skilled in the 10 art to which it appertains to make and use the same.

This invention relates to that type of tool known as a pick, being directed more particularly to a miner's pick.

15 The object of the invention is to furnish a construction in a pick wherein the pick ends or "points" may be removed from the body of the tool for the purpose of being re-shaped.

20 Another object of the invention is the provision of a construction in a pick wherein the points are made removable but secured firmly in place against any chance of falling out.

25 Picks as usually employed comprise a solid head of which the two points are integral parts, requiring that the whole tool be transported to the designated place of repairs for re-shaping. Often the workman is com-

30 pelled to carry a heavy load of these tools at intervals, besides which the pick is out of commission until repaired.

It is my purpose to provide a pick construction, therefore, that will admit of re-35 moving the dulled points and replacing them with others so that the work of mining may proceed without interruption and without requiring an excessive number of the tools, merely having on hand a plentiful sup-

40 ply of the points which may be readily carried in considerable numbers if need be, because they are small and light, which may be changed as often as desired. Furthermore, because of the small size or bulk of the in-45 dividual points they may be more readily and quickly shaped for further use.

In the appended drawing—

Figure 1 is a side elevation of a complete pick involving my invention.

50 Fig. 2 is a longitudinal section of a part of the same shown on a little larger scale.

Fig. 3 is similar to Fig. 2 showing a

slightly different position of some of the parts.

Fig. 4 is an end elevation of the body of 55 the pick.

Fig. 5 shows one of the "points" in perspective, and

Fig. 6 shows a locking-bar for the points.

The body or head of the pick is denoted by 60 1, while 2 is the handle thereof secured therein in any suitable or customary manner.

The said head or body is furnished with a bore 3 extending longitudinally there-through which in the present instance is 65 square in form, Fig. 4, the extremities of the head having a square taper 4 communicating with said bore 3.

In Fig. 5 is shown one of the points, one of which is adapted to seat in each end of the 70 head.

Said point includes a comparatively long tapered working end 5 shouldered at 6 and having a shank 7 tapered in an opposite direction from said tapered end, such shank 75 7 adapted to seat snugly in the tapered socket 4 described. The shank 7 terminates in a square portion 8 filling the bore 3, having a hook-portion 9.

10 is a locking-bar having a hooked end 80 11 to engage the hook-portion 9, as clearly shown in Fig. 2.

Preferably the locking-bar is so placed that its hooks, but one of which is shown, Fig. 2, face in the direction of the handle 85 2, the "back" of the bar being engaged by a set screw 12 in the outer side of the head.

13 is a recess in the side of the head nearest the handle in which is stationed a spring 14 placed under compression by the bar as 90 the set screw 12 is tightened down upon that member, the bore 3 being larger in extent than the bar so that the latter may rise and fall therein to permit locking and unlocking of the pick points. When the screw is loosened the spring will raise the bar to release the hook 9 while a reverse action will positively hold the point in place.

Since the tapered shank 7 of the pick-point fits the tapered socket 4 and the shoulder 6 100 may bear upon the end of the head 1 there is a solid, firm bearing for said point with no looseness whatever and yet easy removal of the point is assured.

Changes may be made in the device without sacrificing the spirit and intent of the invention.

I claim:—

- 5 1. A pick including a one-piece head having a longitudinal bore terminating at one end of the head in an outwardly flared angular recess, a pick-point having a tapered shank corresponding to and adapted to fit 10 into the recess, said shank including a hook to extend into the said bore inward from the recess, said hook lying nearest one of the walls of the bore, a locking-bar lying in and having a diameter less than that of the said 15 bore and having a hook to lie opposite and engage the said hook of the shank, means at one side of the bar to positively move its hook into engagement with the shank-hook, and a device placed under tension by the bar 20 in the movement thereof to engage the hook, the same adapted to separate the two said hooks when said means is actuated to release the bar.
2. A pick including a one-piece head having a longitudinal bore terminating at each end of the head in an outwardly flared recess, a pick-point having a tapered shank corresponding to and adapted to fit into each recess, the shanks each including a 25 hook to extend into said bore inward from each recess, the same lying nearest one of the walls of the bore, a locking-bar lying in the bore having a diameter less than that of the bore and having a hook at each end 30 to engage the hook of each pick-point, means to move the bar laterally to engage the hooks, and a device placed under tension in such movement adapted when said means is 35 retracted to move the bar and disengage the hooks.
- 40 3. A pick including a one-piece head having a longitudinal bore terminating at each end of the head in an outwardly flared re-

cess, a pick-point having a tapered shank corresponding to and adapted to fit into 45 each recess, the shanks each including a hook to extend into said bore inward from each recess, the same lying nearest one of the walls of the bore, a locking-bar lying in the bore having a diameter less than that of the 50 bore and having a hook at each end each to engage one of the hooks of the pick-point, means to move the bar laterally to engage the hooks, a spring at the opposite side of the locking-bar adapted to be compressed 55 when said means is moved to engage said hooks and adapted when the means is retracted to move the bar for disengaging the hooks.

4. A pick including a head having a longitudinal bore terminating at the end of the head in an outwardly flared recess, a pick-point having a shank corresponding in form to and adapted to seat in the recess, said shank including a straight extension fitting 60 the bore terminating in a hook lying nearest one of the walls of the bore leaving a space between it and the other wall of said bore, a locking-bar in said bore less in diameter in one of its measurements than the bore 65 and having a hook to lie permanently in the said space, means to move the locking-bar laterally to carry its hook into engagement with the hook of the shank, and a spring in the path of the said locking-bar compressed 70 by the latter in its movement, said spring adapted to disengage the bar from the hook of the shank when the said means is retracted.

In testimony whereof I affix my signature 80 in presence of two witnesses.

LEWIS O. McELHANEY.
